MECHANICAL PENCIL HAVING MEANS FOR SHARPENING THE LEAD

Elmer H. Kuper, Cheyenne, Wyo., assignor of five per cent to Wilbur A. E. Mitchell, Greeley, Colo.

Application April 24, 1947, Serial No. 743,541

14 Claims. (Cl. 120—15)

1

This invention relates to mechanical pencils, in which the lead is moveable with relation to the guide therefor, and having means for sharpening the lead.

It is a principal object of this invention to provide a pencil having a single spring-tensioned lead sharpening means for sharpening action of the lead as the lead is projected.

Another object of this invention is to provide a pencil having a lead sharpening means which is normally a part of the inner lead supporting guide, constructed to support the lead when not in sharpening position.

Another object of this invention is to provide such a pencil with a method of mounting the lead cutting means whereby it may be replaced with another sharpening means for accomplishing a different angular cutting of the lead when desired.

A further object is to provide a pencil with a novel lead cutting means having a taper governing shoe, normally spring-tensionally resting in the lead channel, and with the taper governing shoe designed to control the angle of the tapered point to be cut in the lead by the cutting edge thereof.

Various other objects and advantages will appear evident from the accompanying drawings and detailed description. Like reference numbers and characters have been used to represent like parts in the different illustrations throughout the drawings, in which

Figure 1 is a longitudinal cross-sectional view of a pencil in retracted position of the plunger;

Figure 2 is a similar view but with the plunger in closed position;

Figure 3 is a cross-sectional view taken upon the line 3—3 of Figure 2;

Figure 4 is a similar view to that shown in Figure 3, but illustrative of another modification of my sharpening means or cutter;

Figure 5 is an enlarged diagrammatical view illustrative of the operation of the lead with my novel cutter means, in different sized construction of the cutter and taper governing shoe, showing the relationship thereof to the degree of taper of the point of the lead capable of being cut thereby;

Figure 6 is an enlarged view of the inner lead guide and sharpening means of Figure 1 positioned before lead sharpening action is commenced.

Figure 7 is a similar view to that shown in Figure 6, but after several longitudinal sharpening strokes of the lead have been caused in one rotary position of the lead;

2

Figure 8 is another enlarged diagrammatical view of my spring-tensioned cutter of Figure 1, illustrative of the positions thereof before and after completion of sharpening operation of the lead, and before the lead is projected outwardly of the pencil;

Figures 9 and 10 are similar views to Figures 6 and 7, respectively, except with the inner guide and outer pencil point being of less tapered dimension, and with a cutting means designed to produce a less tapered point to the lead;

Figure 11 is illustrative of a finished lead sharpening operation of the modification illustrated in Figures 9 and 10, to show the lead supporting action of the cutting means in that finished position.

Numeral 10 designates a barrel or casing open at both ends, and threaded at the point end to receive an inner lead supporting guide member

20 11. The inner guide has a central longitudinal opening 13 designed to receive, support and guide the lead as it is projected forwardly out of the pencil. There is an extension 12 of member 11 provided on one side only thereof opposite the sharpener 14, so that the sharpener 14 may have access to the lead on that side. The inner guide is preferably screw-threaded into the barrel. A sharpening member, generally designated as 14, consisting of a spring-tensioned blade or member is mounted, as illustrated, opposite from the extension 12 and by means of an enlargement 15 thereof being slidably inserted into a groove or slot 34 provided as illustrated in member 11. At the extreme outer end of the sharpener member 14, I provide a slight rounded head enlargement

30 35 thereof 17, having a knife-like lead sharpening blade 16, as illustrated. The enlarged head portion 17 acts as a taper governing shoe, as will be explained. The cutter blade 16, of the head 17, is designed to extend into the path or course of travel of the lead, as it is projected forwardly for

40 extension from the point of the pencil, by virtue of the sharpener 14 comprising a spring-tensioned arm seated at 34. That tension normally causes the taper-governing shoe 17 to rest against the channel side of the extension 12 when the lead is retracted, as in Figure 1. Each time the lead is projected forwardly of the pencil as illustrated, the lead pushes the spring sharpener 14 to one side as the lead is projected forwardly

45 50 between the sharpener head 17 and the extension 12. It will be seen that each time the lead is so projected the cutting edge 16 will shave a small portion off of the lead, as the lead passes the cutting blade 16, as illustrated in Figures 2, 7, and 55 10, due to the tension of member 14 pressing

blade 16 normally into the path of the projected lead. The lead is designated by the numeral 18. Reference numeral 19, of Figures 2, 7 and 10, represents that portion of the lead which will be shaved or cut away in preparing the lead point, upon plunger operation of the pencil, as will be more fully explained. An outer conical hollow pencil point 20 is screw fastened over the inner lead supporting guide, to the barrel, such as by being screw threaded onto an extension of the flange or collar of guide 11, as illustrated. An outer opening 21 is provided at the tip of the point 20, adapted to receive and support the lead as it is projected therethrough, by being substantially of the same diameter as the lead. Referring to the enlarged diagrammatical views 5 and 8, it is to be noted that the extension or lead channel side edge of the cutter head of each sharpening member 14, 14a and 14b, respectively extending from the contact point 16a of each cutter edge opposite the lead channel to the taper-governing shoe 17, 17a and 17b, respectively, is slightly concave in contour, which is designed to help prevent the cutter blade 16 from slipping out of cutting operation during the shaving of the lead. That concavity tends to dig or hold the cutting edge point 16a in the lead, during the projection cutting stroke. That feature is accentuated by the normal spring tensioned pressure of the shank of the member 14 toward the member 12, and assures that the point 16a does not jump out of cutting operation before the outwardly or projected cutting stroke of the lead is completed. That concave contour of 14 may be altered as needed, by substituting different contoured sharpening members 14, illustrated as 14a and 14b in Figure 5, so as to alter the degree of sharpness of the point capable of being cut thereby in the lead. The angle of edge 16 is to be noted as provided to assist the cutting point 16a thereof from slipping out of cutting operation, during sharpening of the lead by 16a, in cooperation with the spring tensioned pressure of the member 14, as explained.

A hollow plunger 22 is slidably inserted into the barrel 10, and has a cut-away portion 23 near the eraser end of the pencil, as illustrated. A projection 32 extends inwardly from a conventional spring clasp 31, designed to act as a stop means in cooperation with cut-away portion 23, for purpose of limiting the normal retractable position of the plunger, as will be more fully explained. Clasp 31 is suitably fastened to the outside of the barrel at 9. An operable conventional lead holding means is provided in the inner opening 25 of the plunger 22, such as by a tube 24 being wedged therein and adapted for rotary movement therein, and having a spiral groove 28 formed therein adapted for receiving a key 27 from a lead holding member 26. Member 26 is adapted for longitudinal movement within tube 24 by its key traveling along groove 28, and has an opening 29, as illustrated, adapted to wedgedly receive one end of the lead 18. A lead removing pin is provided in the other end of the member 26, as will be understood. Tube 24 has an enlarged head adapted for receiving an eraser 33. Turning of the eraser end of the tube 24 causes the key 27 to travel in spiral groove 28 for either projecting or retracting the lead, with relation to tube 24, as will be understood.

Upon an insertion of a piece of lead, illustrated as 18 in Figure 1, and with the plunger in retracted position, the tip of the lead is ready to be sharpened. That is accomplished by operating the plunger 22 toward the point of the pencil in

the barrel 10, by a longitudinal movement or plunger operation of the plunger 22 to the closed position as illustrated in Figure 2. During that plunger projection the point of the lead passes by the cutter edge 16 and the taper governing shoe 17, and a portion of the lead adjacent to the point is thereby sharpened or cut by 16 as illustrated in Figure 2. After several such strokes of the plunger moving the lead by the cutter head, against the spring tension of sharpener member 14, all of the lead capable of being cut will have been cut; and then the plunger and erasers heads are together turned a few degrees, and thereby the lead rotated or turned slightly and the same lead cutting action is repeated; and again the lead is turned a few degrees, as just explained, and the action repeated as often as necessary until a perfect point to the lead has been formed, as illustrated in Figures 8 and 11, as will be readily understood.

It is to be noted that the cutter tip or contact point 16a, in the position of the cutter head illustrated in Figures 1, 5, 6, 8 and 9 before the lead is projected to a point to cause a spreading of the sharpener shank 14 from contact position of the shoe 17 with the lead channel 13, is slightly to the left of the longitudinal center line of the lead indicated as 35. This construction permits of the making of a geometrically perfect lead point, in sharpening the lead, and is a novel feature of my invention. It is further to be emphasized that I use only a single lead sharpening means or member 14, which always makes a perfect lead point after sharpening operation of the lead. Heretofore it has been impossible to make a perfect point, because more than one cutter was used and the cutters were not able to overlap that longitudinal center line of the lead to cause a perfect point to be made, but instead in actual practice they never were able to make a perfect point but a certain amount of blunt or flat surface always remained at the tip of the lead point.

Referring to Figure 5, it will be further obvious that, given my sharpener member common contact point 16a, of different sharpener members, 14, 14a and 14b, having different operating lengths between the contact point 16a of each and the taper governing shoe 17, 17a and 17b, respectively, may be used, which various lengths are represented as A, A' or A''. I provide different sharpening members 14, 14a and 14b, each having a different operating length, adapted for use with each pencil. Those sharpening members are interchangeable, by means of the tongue 15 of a member being removably inserted in groove 34, should it be desired to provide a sharpening member capable of cutting a different type point than the one being used. Each of my sharpening members 14, 14a and 14b, have substantially one common characteristic, namely the type of cutting edge 16, and the angle "B" thereof, as illustrated, and each with a contact point 16a as illustrated in Figure 5. The only variation, between different members 14, 14a and 14b, adapted to cut differently tapered lead points, is in the concavity of the taper shoe 17, 17a and 17b thereof, respectively, and the length thereof from point 16a to the extreme end 17, 17a and 17b, as illustrated in Figure 5, thereby defining the longitudinal angular line extended between the point 16a and the shoe as shown by T, T' and T'' of Figure 5. The cutting member 14, illustrated in full lines in that Figure 5, will effect a lead taper or point capable of being cut in the lead, upon cutting operation, having an angular degree of taper or point illustrated by the reference char-

acter T. The next head of the cutting member illustrated as 14a in dotted lines with the distance A', between its contact point 16a and the taper governing shoe 17a, will cut an angular point illustrated by the reference character T'; and the largest cutter head there illustrated as 14b in dotted lines, having a distance A'' between the cutter contact point 16a and its taper governing shoe 17b, will cause a sharp or fine tapered point to be cut in the lead of an angle represented by the reference character T''.

Referring to the taper governing shoe head or enlargement 17, of member 14, illustrated in solid lines of Figure 8, it will be clear that in the beginning of cutting operation, when the lead is projected in the channel 13 to a point indicated as "P," the lead presses against the shank of the member 14 and thereby causes it to be moved outwardly of the lead channel, against the spring tension of that member 14, or as illustrated there to the right as the lead is projected. Figures 9, 10 and 11 illustrate the type of a pencil, such as a carpenter's pencil or other industrial crayon, where a duller point is preferable, using a sharpening member 14c, having a contact edge 16c and a taper shoe 17c.

In Figure 4 I have illustrated another preferred embodiment of my sharpening member 14, with the cutter 16a and taper governing shoe 17 being of cross-sectionally crescent-shape or design, rather than to have the knife 16a of straight edge. Such crescent-shaped cutter construction will permit a point to be cut with fewer rotary plunger operations of the lead against same. The reference character D indicates the angle of the cutter edge 16 to the line of taper cut in the lead by the cutter. I make that angle always greater than a right angle in all modifications of 14.

In operation, to disassemble my pencil for replacing or changing leads the plunger is removed from the barrel 10 by lifting the projection 32 at the top of the spring clasp 31, outwardly from the barrel. This can be accomplished by an insertion of a fingernail against the inner side of the ridge 8, which is provided for that purpose, and the projection pulled outwardly, on the seat or pivot 9 of the spring clasp, against the tension of the elongated spring portion 31a, as will be understood; and a similar springing of the projection 32 is accomplished to permit reinsertion of the plunger 32 into the barrel.

The sharpening member 14, being removably fastened at 34, is adapted to be replaced, should dullness occur, or should a different member be desired to produce a different tapered point in the lead, as illustrated in Figure 5. Outer point 20 is first removed, and then inner point 14, if desired, in replacing member 14, though the operation may be accomplished only by removing the outer point 20 and then slipping the tongue of 14 out of its groove and replacing or substituting with the tongue of the next member 14, and replacing the point 20.

Having thus described these preferred embodiments of my invention, it will be readily be seen that many and numerous changes can be made therein, such as of proportion, size, relationship or parts and cutter size, position and angle, and of other construction, and therefore I wish it to be distinctly understood that I wish to be bound only by and within the scope of the appended claims.

What I claim and desire to secure by Letters Patent is:

1. In a pencil having a point, a barrel, an op-

erable lead in the barrel, and means in the barrel for holding the lead and adapted for longitudinal and rotatable movement of the lead with relation to the point, the combination therewith of an inner lead supporting means adjacent the point, and a single spring-tensioned knife lead sharpening means, removably secured to said lead supporting means, for sharpening the lead as the lead is projected outwardly of the pencil, said sharpening means being adapted to act as additional lead supporting means when the lead is fully projected therebeyond.

2. A pencil as claimed in claim 1, and characterized by the provision of the lead sharpening means positioned at an angle of less than 90° to the lead projection longitudinal center line, and the sharpening means having a taper governing shoe for controlling the angle of taper of the lead point to be formed upon movement of the lead with relation to the sharpening means.

3. In combination with a pencil having a removable point and means for operating the lead longitudinally and rotatably with relation to the point, of an inner lead supporting means removably mounted adjacent the point, and a single spring-tensioned lead sharpening member positioned so as to normally rest in the path of the lead when the lead is retracted therebeyond and adapted for a cutting of the lead only upon an outward projection of the lead, said spring-tensioned sharpening member being removably carried as a part of and by the inner lead supporting means and comprising a part of said lead supporting means when the lead is projected outwardly beyond the sharpening member.

4. The combination as claimed in claim 3 and characterized by the addition of the lead sharpening and supporting means having a taper governing shoe for controlling the taper angle of the point to be formed in the lead upon outward projective movement of the lead with relation thereto.

5. In a pencil having a barrel and an inner lead supporting guide within the barrel, and a lead rotatably and longitudinally movable in said guide, the combination therewith of a single spring-tensioned sharpening means for sharpening the lead upon projective movement thereof.

6. A pencil as defined in claim 5, and characterized by the definition of the sharpening means having a taper governing shoe and a cutting point and the taper governing shoe being adapted to assist as lead supporting means in cooperation with the guide in the projected lead use of the pencil, and said taper governing shoe also comprising means for disengaging said cutting point from the lead upon projection of the lead beyond the taper governing shoe.

7. In a pencil having an outer point, a barrel, a lead therein, means for operating the lead longitudinally and rotatably, and inner lead supporting means adjacent the point comprising an inner lead point supporting channel, in combination therewith a removable spring-tensioned one-directional cutting means included as a part of said inner lead supporting means, said cutting means being adapted for sharpening the lead upon longitudinal movement of the lead in different rotatorial positions of the lead and for supporting the lead when the lead is projected outwardly therebeyond.

8. A pencil combination as set forth in claim 7, and characterized by the definition of the removable spring-tensioned one-directional cutting means comprising a knife means adapted for sharpening operation of the lead only upon pro-

jection of the lead and having a cutting point and a taper governing shoe, said cutting means being positioned so that its tension normally holds the cutting point thereof in the path of the lead after the lead is retracted inwardly therebeyond, and said cutting point being adapted to extend from one side of the lead to beyond the longitudinal center line thereof when the lead is retracted therebeyond, said taper governing shoe extending outwardly of the cutting means with relation to the pencil point and from the cutting point and being adapted for controlling the angle of taper cut in the lead by the cutting point upon outward projection of the lead, and said taper governing shoe portion of the cutting means being the only portion of the cutting means being in lead contact as part of the inner lead supporting means when the lead is projected outwardly therebeyond.

9. In a pencil having a barrel, an inner lead supporting guide within the barrel, and a lead rotatably and longitudinally movable in said guide, in combination therewith a single spring-tensioned sharpening means associated with the guide for supporting the lead upon outward projection of the lead and comprising additional lead supporting means cooperating with the guide, said sharpening means having a cutting edge and a taper governing shoe, said shoe being positioned to normally press against the lead supporting guide channel when the lead is retracted, said cutting edge having a cutting contact point, said sharpening means having an angular relationship between the contact point thereof and the taper governing shoe lead channel side surface adapted for controlling the angular taper of the point adapted to be cut in the lead by the cutting edge upon outward projection of the lead in different rotarial positions of the lead.

10. In combination, a pencil of the class described having a rotatable and outwardly projectible lead, a hollow outer point for the lead, an inner lead supporting means adjacent and within the point, and a spring-tensioned sharpener knife means associated within and adjacent the point and being removably mounted and comprising a part of said supporting means, said knife means comprising a cutting point adapted to extend from one side of the lead to beyond the extended longitudinal center line of the lead when the lead is retracted therebeyond, said cutting point extending at an angle greater than a right angle with relation to the line of taper point cut in the lead by the knife means upon plunger operation of the lead, said cutting point being normally spring tensionally held in the path of the lead when the lead is retracted therebeyond, said knife means also having a taper governing shoe means adapted to ride against the lead after sharpening operation and when the lead is projected therebeyond, and said cutting point being adapted to be out of cutting contact relationship with the lead when the lead is projected beyond the taper governing shoe.

11. A pencil combination as described in claim 10, and characterized by the definition of said knife means having its taper governing shoe and cutting point connected by a concave extension, and the extended line between said cutting point and taper governing shoe, being of an angle with relation to the longitudinal center line of the lead, adapted for controlling the angle of the tapered point cut in the lead by the knife means during lead sharpening longitudinal and rotary

operation of the lead with relation to said knife means.

12. The combination with a pencil having a plunger actionable and rotatable lead of a removably mounted one-directional spring-tensioned single knife lead sharpening means adapted for cutting a perfect geometrical point on the lead upon projection and rotary movements of the lead with relation thereto, said knife means having a cutting point normally extending from one side of the lead to a point beyond the longitudinal center line of the lead when the lead is retracted into the pencil therebeyond, and said knife means having means for lifting the cutting point out of lead contact after the point has been formed on the lead and the lead has been projected outwardly of the pencil and therebeyond said last named means.

13. The combination with a pencil having a barrel, an inner lead guide and supporting member removably fastened to said barrel and having an extension therefrom and a lead receiving channel therein, a cut away portion on one side of said extension, an outer point removably encasing the inner lead supporting guide, a plunger slidably mounted in the barrel, a lead operably mounted in said plunger, means associated with the plunger for effecting rotary and longitudinal movement of the lead with relation to said lead guide, a spring pocket clasp attached to the outer side of the barrel and having a spring tensioned projection movably positioned in a limited recess in said barrel for limiting the plunger operation with relation to the barrel, a peripheral recess on the exterior of the plunger adapted to receive the spring projection from the clasp, said plunger being adapted to be removed from the barrel upon spring tension disengagement of the projection of the clasp out of the recess on the plunger, of a single lead sharpening member spring-tensionally and removably mounted in said inner lead supporting guide on the side thereof adjacent the cut away portion and the point of the pencil and adapted to be normally positioned in the lead receiving channel, said sharpening member comprising a cutting head having a cutting edge and cutting contact point and a taper governing shoe, said sharpening member being adapted to cut a portion of the lead at the end thereof into a substantial point upon each longitudinal projection of the lead outwardly of the pencil and between the cutting head on the one hand and the extension of the inner lead guide on the other hand, said lead sharpening taper governing member having a portion normally adapted to rest against the lead after the lead has been projected outwardly of the pencil in tensioned relationship therewith and on the side thereof in the cut away portion of the extension of the inner lead guide, whereby said sharpening member also acts as lead supporting means in that projected position of the lead therebeyond, and whereby the angle of the taper governing shoe with relation to the contact point of the cutting edge of the sharpening member controls the angle of taper of the point formed in the lead as the lead is projected longitudinally of the pencil, in different rotary positions of the lead.

14. A spring-tensioned sharpener knife, adapted to be removably carried at one end thereof by the point of a pencil of the class described having a longitudinally projectable and rotatable lead, comprising a spring-tensioned shank and a knife blade having a cutting point and a taper govern-

ing shoe at its other end, said cutting point being adapted to be normally extended from one side of the lead to beyond the longitudinal center line of the lead, when the lead is retracted therebeyond, by said tension shank, said blade comprising the extension between the shank and the cutting point and being adapted to sharpen the lead upon projective movement of the lead thereagainst, and said taper governing shoe being adapted to ride against the lead and to lift the cutting point out of cutting contact with the lead upon projective movement of the lead therebeyond, the knife surface between the cutting point and the taper governing shoe being of concave contour.
